COMMUTATOR BRUSH HOLDER

Martin J. Neuner, Fairview, N. J., assignor to
Bendix Aviation Corporation, Teterboro, N. J.,
a corporation of Delaware

Application September 2, 1944, Serial No. 552,454

10 Claims. (Cl. 171—324)

1

My invention relates to commutator brush holders and particularly to means for varying the pressure applied to commutator brushes.

One of the objects of my invention is to provide pressure regulating means which is so constructed and arranged whereby the pressure applied to the commutator brushes of an electrical device may be readily varied to effect efficient operation of the device.

Another object of my invention is to provide means of the foregoing described character which is so constructed and arranged whereby the pressure applied to the brushes may be adjusted to a relatively minute degree to prolong the effective use of the brushes and to minimize wear of the commutator.

An important object of my invention is to provide means of the character described which is simple in construction, durable in use, efficient in operation and economical in manufacture.

With the above and other objects in view, as will hereinafter appear, the invention consists in the combination, and arrangement of parts hereinafter set forth and illustrated in the accompanying drawings, from which the several features of the invention and the advantages attained thereby will be readily understood by those skilled in the art.

Referring to the drawings, wherein like reference characters designate like parts throughout the several views—

Figure 1 is a perspective view of my invention and illustrates the same in conjunction with a commutator and brush assembly of an electrical device.

Figure 2 is a transverse sectional view of the invention illustrated in Figure 1.

Figure 3 is a sectional view taken on the line 3—3 of Figure 2.

Figure 4 is a disassembled perspective view of the invention.

Figure 5 is a detail longitudinal section of a modified form.

Figure 6 is a sectional view taken on the line 6—6 of Figure 5.

Figure 7 is a detail disassembled perspective view of the toothed end of the sleeve and the collar disclosed in Figures 5 and 6.

The present invention is illustrated in conjunction with the commutator 10 and insulating ring 11 of an electric motor of the engine starter type; the ring 11, as is customary, being secured to an end partition or wall of the motor casing 13 and having fastened thereto a set of brush brackets 12. Inasmuch as the brackets 12 are of

an identical construction, a detailed description and illustration of one, together with its associated components forming part of the present invention, will suffice.

As depicted in the drawings, the bracket 12 houses a pair of brushes 13 which are equipped with the usual lead wires 14 and L-shaped lifters 15, each of the latter having a flange 16 coating with the adjacent end face 17 of the brush to slidably maintain therebetween the outer rolled end 18 of a brush actuating arm 19. Adjacent the ring, the end of the bracket 12 is formed with a laterally extending ear 20 to which is fixed the inner end of a shaft 21 having mounted thereon a sleeve 22 formed with an elongated slot 23. Rotatably mounted on the sleeve are a pair of spring retainers or carriers 24 each comprising a pair of spaced centrally apertured discs 25, through which the sleeve extends, and which discs 25 are secured together by a bridge 26 integrally connected to the opposite end of the arm 19.

Each carrier 24 has disposed therein, between the discs 25, a flat type coil spring 27 having its inner end 28 anchored in the slot 23 and its outer end formed with a hook 29 embracing the bridge 26 to transmit tension to the brush 13 through the arm 19. As illustrated in the drawings, one of the discs 25 of each carrier is fashioned with a finger 30 adapted to be engaged by means (not shown) to effect partial rotation of the carriers in a direction to disengage the brushes from the commutator to permit the commutator to be manually or otherwise rotated when desired.

Primarily, the present invention is directed to controlling or regulating the pressure applied to the brushes in their lower or commutator engaging positions and in a precise manner whereby the pressure may be varied to within a relatively minute degree, it being understood that reducing the pressure applied to the brushes, comparable with efficient operation of the motor, serves to prolong the life and effectiveness of the brushes with resultant reduction in the wear of the commutator. As illustrated in Figures 1 to 4 inclusive, means is provided for regulating the pressure applied to the brushes, and which means comprises the shaft 21 and the sleeve 22, the latter having fixed to or formed with its inner end, adjacent the ear 20, an internal gear or interiorly toothed annular case 31, in which is normally maintained and in fixed relation therewith, a pinion or toothed collar 32, the teeth 33 of the latter intermeshing with the teeth 34 of the case, it being understood that the case and

collar are provided with a multiplicity of relatively small and closely spaced teeth whereby rotative adjustment of the sleeve 22 with relation to the shaft 21 may be effected in small steps. By axially moving the sleeve 22 with respect to the shaft 21, the sleeve may be rotated to vary the tension of the springs to a desired degree and to maintain the same upon reverse axial movement of the sleeve and intermeshing of the teeth 33 and 34.

The outer end of the shaft extends beyond the outer end of the sleeve and is formed with a circumferential groove 35 in which is disposed a split resilient removable ring 36 for precluding axial movement of the sleeve relative to the shaft thus insuring meshing of the teeth, it being understood that the ring is removed to permit adjustment of the sleeve relative to the shaft to vary the tension of the springs.

In the form illustrated in Figures 5, 6 and 7, the inner end of the shaft 21 is squared as at 49 and has fixed thereon a toothed collar or case 42 which receives the toothed inner end 43 of the sleeve 22, the teeth of said case and end intermeshing to preclude relative rotation of the shaft and sleeve as in the instance of the embodiment disclosed in Figures 1 to 4 inclusive.

In order to facilitate application of the ring 36 into the groove 35, the outer end face of the shaft is provided with a conical recess 56 for receiving therein the conical end 51 of a spreading tool 52 having a cylindrical portion 53 of a diameter coincident with the diameter of the shaft and defining a shoulder or end face 54, adjacent the conical portion, for butting engagement with the outer end face of the shaft, whereby, an expanded ring 36, contained on the cylindrical portion 53, may be moved over the outer end of the shaft and snapped into the groove 35 as clearly illustrated in Figure 5 of the drawings.

Without further elaboration the foregoing will so fully explain the invention that others may, by applying current knowledge, readily adapt the same for use under various conditions of service. Moreover, it is not indispensable that all the features of the invention be used conjointly since they may be employed advantageously in various combinations and sub-combinations.

It is obvious that the invention is not confined to the therein described use therefore as it may be utilized for any purpose to which it is adaptable. It is therefore to be understood that the invention is not limited to the specific construction as illustrated and described as the same is only illustrative of the principles of operation, which are capable of extended application in various forms, and that the invention comprehends all construction within the scope of the appended claims.

What is claimed is:

1. In combination, a housing equipped with a movable brush, and pressure applying means for said brush comprising a shaft element fixed to said housing, a sleeve element mounted on said shaft element, one of said elements being provided with an interiorly toothed case and the other being provided with a toothed disc disposed in said case and having its teeth intermeshing with the teeth of said case to preclude relative rotation of said elements, a carrier rotatably mounted on said sleeve element and having an arm engaging said brush for applying pressure thereto, a spring disposed in said carrier and having its ends connected to said sleeve and said arm respectively for maintaining the latter in

engagement with said brush, said disc and case being axially separable to permit rotative adjustment between said elements to vary the tension of said spring.

5 2. In combination, a housing equipped with movable brush, and pressure applying means for said brush comprising a shaft element fixed to said housing, a sleeve element mounted on said shaft element, one of said elements being provided with an interiorly toothed case and the other being provided with a toothed disc disposed in said case and having its teeth intermeshing with the teeth of said case to preclude relative rotation of said elements, a carrier rotatably mounted on said sleeve element and having an arm engaging said brush for applying pressure thereto, a spring disposed in said carrier and having its ends connected to said sleeve and said arm respectively for maintaining the latter in engagement with said brush, said disc and case being axially separable to permit rotative adjustment between said elements to vary the tension of said spring, and removable means carried by one of said elements for precluding axial displacement of the other element relative thereto.

3. In pressure applying means for a brush movable within a housing, a shaft element adapted to be fixed to said housing, a sleeve element on said shaft element, one of said elements being provided with an interiorly toothed case and the other being provided with a toothed disc disposed in said case and having its teeth intermeshing with the teeth of said case to preclude relative rotation of said elements, a carrier rotatably mounted on said sleeve element and having an arm for engaging said brush to apply pressure thereto, a spring disposed in said carrier and having its ends connected to said sleeve and said arm respectively for maintaining the latter in engagement with said brush, said disc and case being axially separable to permit rotative adjustment between said elements to vary the tension of said spring.

4. In pressure applying means for a brush movable within a housing, a shaft element adapted to be fixed to said housing, a sleeve element mounted on said shaft element, one of said elements being provided with an interiorly toothed case and the other being provided with a toothed disc disposed in said case and having its teeth intermeshing with the teeth of said case to preclude relative rotation of said elements, a carrier rotatably mounted on said sleeve element and having an arm for engaging said brush to apply pressure thereto, a spring disposed in said carrier and having its ends connected to said sleeve and said arm respectively for maintaining the latter in engagement with said brush, said disc and case being axially separable to permit rotative adjustment between said elements to vary the tension of said spring, and removable means carried by one of said elements for precluding axial displacement of the other element relative thereto.

5. In combination, a housing equipped with a movable brush, and pressure applying means for said brush comprising a shaft fixed to said housing and provided with a toothed disc, a sleeve mounted on said shaft and provided with an interiorly toothed case receiving said disc and having its teeth intermeshing with the teeth of said disc to preclude rotation therebetween, a carrier rotatably mounted on said sleeve and having an arm engaging said brush for applying

pressure thereto, a spring disposed in said carrier and having its ends connected to said sleeve and said arm respectively for maintaining the latter in engagement with said brush, said sleeve being axially movable on said shaft to separate said case and disc to permit rotation of said sleeve on said shaft to vary the tension of said spring.

6. In combination, a housing equipped with a movable brush, and pressure applying means for said brush comprising a shaft fixed to said housing and provided with a toothed disc, a sleeve mounted on said shaft and provided with an interiorly toothed case receiving said disc and having its teeth intermeshing with the teeth of said disc to preclude rotation therebetween, a carrier rotatably mounted on said sleeve and having an arm engaging said brush for applying pressure thereto, a spring disposed in said carrier and having its ends connected to said sleeve and said arm respectively for maintaining the latter in engagement with said brush, said sleeve being axially movable on said shaft to separate said case and disc to permit rotation of said sleeve on said shaft to vary the tension of said spring, and removable means carried by one of said elements to precluding axial displacement of the other element relative thereto.

7. In pressure applying means for a brush movably mounted in a housing, a shaft adapted to be fixed to said housing and provided with a toothed disc, a sleeve mounted on said shaft and provided with an interiorly toothed case receiving said disc and having its teeth intermeshing with the teeth of said disc to preclude rotation therebetween, a carrier rotatably mounted on said sleeve and having an arm for engaging said brush for applying pressure thereto, a spring disposed in said carrier and having its ends connected to said sleeve and said arm respectively for maintaining the latter in engagement with said brush, said sleeve being axially movable on said shaft to separate said case and disc to permit rotation of said sleeve on said shaft to vary the tension of said spring.

8. In pressure applying means for a brush movably mounted in a housing, a shaft adapted to be fixed to said housing and provided with an interiorly toothed case, a sleeve mounted on said shaft and provided with a toothed end section disposed in said case and having its teeth intermeshing with the teeth of said case to preclude rotation therebetween, a carrier rotatably mounted on said sleeve and having an arm for engaging said brush for applying pressure thereto, a spring disposed in said carrier and having its ends con-

nected to said sleeve and said arm respectively for maintaining the latter in engagement with said brush, said sleeve being axially movable on said shaft to separate said end section from said case to permit rotation of said sleeve on said shaft to vary the tension of said spring.

9. In pressure applying means of the type provided with a carrier equipped with an arm for exerting pressure on a brush movable within a housing and with the carrier having a spring connected to the arm for exerting said pressure; a pair of telescopically arranged members adapted to extend through said carrier and having end sections formed with intermeshing teeth for precluding relative rotation of said members, one of said members adapted to be connected to said spring to vary the tension thereof upon rotation relative to the other member, one of said members being axially movable relative to the other to demesh said teeth and permit rotative adjustment of said members.

10. In combination, a housing equipped with a movable brush, and pressure applying means for said brush comprising a shaft element non-rotatively fixed to said housing, a sleeve-like element mounted on said shaft element, one of said elements being provided with a case having interior tooth means and the other being provided with a member disposed in said case and having tooth means, the tooth means of said elements intermeshing with each other to prevent rotation of the elements relative to each other, a carrier rotatably mounted on said sleeve-like element and having an arm engaging said brush for applying pressure thereto, and spring means connected between said sleeve and said arm for maintaining the arm in engagement with the brush, said member and case being adapted for movement including rotation relative to each other to vary the force imposed by said spring means relative to the brush.
